[57] CLAIM

The ornamental design for a work cart, substantially as shown and described.

DESCRIPTION

FIG. 1 is a side elevational view of a work cart, showing our new design, the opposite side elevational view being a mirror image of that shown;

FIG. 2 is a top plan view thereof;

FIG. 3 is a front elevational view thereof;

FIG. 4 is a rear elevational view thereof;

FIG. 5 is a bottom plan view thereof;

FIG. 6 is a side elevational view of a work cart, showing a second embodiment, the sole difference from the first embodiment being in the three wheels attached thereto;

FIG. 7 is a front elevational view of FIG. 6;

FIG. 8 is a rear elevational view of FIG. 6;

FIG. 9 is a bottom plan view of FIG. 6;

The top view of the second embodiment of a work cart is identical to the top view of the first embodiment shown in FIG. 2.
